UNITED STATES PATENT OFFICE.

JOHN MURRAY GUILBERT, OF PHILADELPHIA, PENNSYLVANIA.

PAPER BOX.

SPECIFICATION forming part of Letters Patent No. 588,423, dated August 17, 1897.

Application filed November 14, 1895. Serial No. 568,913. (No model.)

To all whom it may concern:

Be it known that I, JOHN MURRAY GUILBERT, a citizen of the United States, residing in the city and county of Philadelphia, State 5 of Pennsylvania, have invented a new and useful Improvement in Paper Boxes, which improvement is fully set forth in the following specification and accompanying drawings.

My invention relates to paper boxes; and 10 it consists of a novel construction of partition for the same, the said partition being provided with tabs and being bent up in the novel manner hereinafter described, whereby the different portions of the same can be easily 15 caused to assume the desired positions and readily placed in position in the box, so as to divide the same into the required number of compartments, all as will be hereinafter set forth.

Figure 1 represents a plan view of a blank 20 from which partitions for a paper box embodying my invention are constructed. Fig. 2 represents a transverse section on line $\alpha\alpha$, Fig. 1, showing the relative position of the scorings. Fig. 3 represents a perspective view of 25 a box with partitions therein embodying my invention. Fig. 4 represents a perspective view of a portion of the box, showing a tapering partition therein to be hereinafter referred 30 to. Fig. 5 represents a perspective view of an end of the box, showing the outer portion thereof turned over the tabs of the partition.

Similar letters of reference indicate corresponding parts in the several figures.

Referring to the drawings, A designates a 35 blank from which the novel partitions employed are constructed, said blank consisting of the body portion B, which in the present instance is of quadrilateral shape and has attached to the ends thereof the tabs or extensions C C and D D.

E, F, G, and H designate scores in the blank 40 A, the same extending in the present instance parallel to each other and to the longer sides of said blank, it being noted that said scores F F and G G are each two in number, for a purpose to be hereinafter explained.

K designates longitudinally-extending portions 45 of the blank outside of the scores E and H, said portions K forming feet which are adapted to rest in the bottom of a box and to be gummed, pasted, or otherwise attached

thereto, while the tabs C and D are to be gummed, pasted, or otherwise secured to the ends of the box.

C' C' and D' D' designate scores which are in alinement with the ends of the blank A, as will be understood.

The operation is as follows: The blank A, having been scored as indicated in Figs. 1 and 2, is bent up into the shape seen in Fig. 3, the portion between the scores F and G forming the top M, while the portion between the scores G and H and E and F form the sides L, the feet K being deflected laterally and the tabs or extensions D being bent in the manner indicated, the partition M' being now formed and adapted to be placed in the box, as indicated in Fig. 3, it being evident that when there is a plurality of partitions the 70 edges of the tabs D abut against each other, and thus cause the body of each of the completed partitions to extend parallel with each other, thereby constituting a simple and effective means for dividing up boxes which are adapted for various purposes—such as holding neckties, articles of apparel, &c.—it being understood that the scores are on the under side of the partitions when bent up, as seen in Fig. 3.

When it is desired to employ a wedge-shaped or tapering partition, as seen in Fig. 4, the scores instead of running parallel, as seen in Fig. 1, are caused to converge toward each other, whereby when the parts are properly bent up, as indicated, the tapering partition L' will be formed, the differences between the same and the partition M', having parallel sides, being readily apparent.

Especial attention is also called to the feature of providing the scores F and G in pairs at the points indicated, so that when the board is bent the said scores will be on the inner side of the partition, and the outside of said partition at the folds M' will present an unbroken surface, whereby a neat finish is given to the partition, and re-covering of the same is avoided after it is formed up.

In the present instance the scores F and G are employed as stated, but, if desired, the same may be made by compressing or otherwise bending the board.

It will be seen that by bending the blank A as described a hollow partition is formed

having a top M and the tabs D, which are adapted to be freely movable, and when in position form a lining for the inner end walls of the box.

5 If desired, at the points where the tabs contact with the box the outer cover N thereof may be turned over and secured to said tabs D, as seen in Fig. 5 and dotted lines, Fig. 3, whereby the same will be held in position. At 10 the points opposite the top of the hollow partitions the outer cover N is turned in between said top and the wall of the box.

Having thus described my invention, what I claim as new, and desire to secure by Letters

15 Patent, is—

1. A hollow partition for boxes, formed of a blank having the double scoring F, G, and the single outer scoring E, H, on its under face and provided with tabs between the 20 scorings E, F, and G, H, respectively.

2. A hollow partition formed of a single piece of material having folds, the outer surfaces of which are unbroken, a top portion, and tabs attached to said partition, capable 25 of being bent, in combination with a paper box, against suitable portions of which, said tabs are adapted to contact, the outer cover of said box being lapped over, and secured to said tabs, adjacent the points, where the

same contact with the walls of said box, and 30 at the points opposite the top of the said partition, the said outer cover is turned in between said top and the wall of said box.

3. The combination of a box with a hollow partition formed of a single piece of material 35 having folds, the outer surfaces of which are unbroken, said partition being provided with upright sides and a top portion, laterally-deflected feet K attached to said partition and adapted to rest on the bottom of said box, 40 and tabs D extending at an angle to the upright sides and adapted to abut against the ends of said box.

4. A hollow partition formed of a single piece of material having folds, the outer surfaces of which are unbroken, a top portion, upright sides and tabs attached to said partition capable of being bent, in combination with a box against suitable portions of which 45 said tabs are adapted to contact, the outer portion of said box being lapped over and secured to said tabs near the points where the same contact with the walls of said box, the extremities of said tabs abutting.

JOHN MURRAY GUILBERT.
